UNITED STATES PATENT OFFICE.

CHRISTIAN AUGUSTUS ALBRECHT, OF BERLIN, GERMANY, ASSIGNOR TO THE MERTHALER LINOTYPE COMPANY, A CORPORATION OF NEW YORK.

TYPOGRAPHICAL MACHINE.

1,135,423.

Specification of Letters Patent. Patented Apr. 13, 1915.

Application filed May 23, 1914. Serial No. 840,459.

To all whom it may concern:

Be it known that I, CHRISTIAN AUGUSTUS ALBRECHT, a citizen of the United States of America, at present residing at Chausseestrasse 23, Berlin, N. 4, in the Empire of Germany, have invented new and useful Improvements in Typographical Machines, of which the following is a specification.

The present invention relates to improved means for quick changing a magazine in a multiple magazine composing and distributing machine and is advantageously applicable to multiple magazine typographical composing, line casting, and distributing machines of the Mergenthaler type commercially known under the trade mark "Linotype." Quick changing means for machines of the type just defined are known in which the plurality of magazines is carried upon series of vertical cams symmetrically arranged and having their axes in a plane parallel with that of the plurality, the magazine frame being provided with antifriction rollers engaging with the cams.

The present invention consists in the combination with such a series of cams, of a hand lever by which the cams on one and the same axis can be operated by the machine operator, links from those cams to the others of the series so as to operate them in unison, means by which the initial portion of the movement common to all the cams shall disengage the matrix escape- 35 ment rods from the magazine to be quick changed and the magazine entrance common to the plurality from both the distributor and the entrance mouth of that magazine.

The accompanying figure is a side elevation of a preferred constructional form of the application of the invention to a machine of the type above mentioned.

1 is the fixed distributor, and 2 the magazine entrance pivoted at 3 to the machine frame (not shown). The plurality shown comprises only two magazines 7 and 8 carried in the usual way on a magazine frame 4, which is arranged in the machine frame so as to be raised and lowered by a series 50 of cams, of which only two, 5 and 6, are shown. As there are only two, a single rise

on a cam suffices. It is obvious there must be an additional rise on each cam for each additional magazine.

9, 9 are antifriction rollers between the 55 frame 4 and the cams.

10 is the hand lever fast on the shaft 11 of the front cams 5, and 12 is a link, or one of the, links from a front cam 5 to its rear fellow cam 6, the connections 13 of each 60 link-end to the respective cam being pivotal and near to its magazine frame rise.

14, 14 are the usual escapements and 15 one of the row of escapement rods embraced by a yoke 16 movable horizontally to and 65 fro to put the noses of the said rods out of working connection with the escapements of the magazine to be changed and into working connection with those of the substituted magazine.

70 17 is a rearwardly extended frame carrying the yoke 16 and adapted to move it as stated, by the engagement of an eye 18 at each end on a suitably supported horizontal rod 19. The frame 17 is moved by the front 75 cams 5 which are duplex inasmuch as each has a special rise 20 for this purpose. As soon as the lever 10 is started, a rise 20 rocks the top end of a lever 21 fulcrumed on a stationary fulcrum 22 and in constant engagement with that rise, to the rear, thereby making the bottom arm of the lever 21 push the frame 17 to the front, thereby disengaging the rods 15 from the escapements 80 of the magazine to be changed. This disengagement is accompanied by the rocking back of the magazine entrance 2 on its pivot 3, which rocking back is effected by an arm 23 fast on the fulcrum 22, a second arm 24 fast on the pivot 3 and a link 25 connecting their outer ends. 26 is an adjustable connection between the frame 17 and the bottom end of the lever 21.

85 27 is a notch properly positioned in the periphery of the rise 20 to engage the top 95 end of the lever 21 whenever the escapement rods 15 are in working connection with a row of escapements and to lock them there.

100 The reversal of the lever starts the magazine frame 4 and as soon as the substitute magazine is in composing position, the mag-

azine entrance 2 and the escapement rods are returned to their working position, and the former locked there.

Having described my invention I declare that what I claim and desire to secure by Letters Patent is:—

1. The combination in means for quick changing one of a plurality of magazines in a typographical composing and distributing machine, with a magazine supporting frame, series of cams for raising and lowering it and antifriction devices between the said frame and cams, of links connecting the front series of cams with the back series, and a manual lever fast to the front series for working both series.
2. The combination in means for quick changing one of a plurality of magazines in a typographical composing and distributing machine, with a magazine-supporting frame, series of cams for raising and lowering it, and antifriction devices between the said frame and cams, of links connecting the front series of cams with the back series, a manual lever fast to the front series for working both, a second rise positioned on each cam of the front series to anticipate the magazine-frame raising function of the two series, a yoke embracing the magazine escapement rods, the said escapement rods, a movable frame carrying that yoke, a magazine entrance coöperating with the magazine in operative position, and means actuated by the said second rise to make the said frame put the escapement rods out of working connection with the escapement of, and to also rock the magazine entrance out of working connection with, the operative magazine.
3. The combination in means for quick changing one of a plurality of magazines in a typographical composing and distributing machine, with a magazine-supporting frame, series of cams for raising and lowering it, and antifriction devices between the said frame and cams, of links connecting the front series of cams with the back series, a manual lever fast to the front series for working both, a second rise positioned on each cam of the front series to anticipate the magazine-frame raising function of the two series, a yoke embracing the magazine escapement rods, the said escapement rods, a movable frame carrying that yoke, a magazine entrance coöperating with the operative magazine, means actuated by the said second rise to make the said frame put the escapement rods out of working connection with the escapements of, and to also rock the magazine entrance out of working connection with, the operative magazine, and means for locking the escapement rods in working connection with any coöperating set of escapements.
4. In a typographical machine, the combination of a fixed assembling throat, a magazine movable into and out of registration therewith and provided with a series of escapements, a series of actuating devices connected to the escapements, and means whereby the movement of the magazine out of registration with the assembling throat will effect the disconnection of the escapements and their actuating devices.

5. In a typographical machine, the combination of a magazine provided with a series of escapements, means for moving the magazine, a series of actuating devices for the escapements, means for moving the actuating devices out of operative relation to the escapements, and a common operating device connected directly to both said means.

6. In a typographical machine, the combination of a plurality of magazines each provided with a series of escapements, and movable as a whole to bring one or another magazine into operative position, a series of actuating devices for the escapements of the operative magazine and located in the path of movement of the magazines, and means whereby the movement of the magazines will shift the actuating devices out of the path of movement of the magazines.

7. In a typographical machine, the combination of a plurality of magazines each provided with a series of escapements, means for moving the magazines as a whole to bring one or another into operative position, a series of actuating devices for the escapements of the operative magazine, and means operated directly by the magazine moving means for shifting the actuating devices out of operative relation to the escapements.

8. In a typographical machine, the combination of a plurality of magazines each provided with a series of escapements and movable as a whole in a straight inclined path to bring one or another magazine into operative position, a series of actuating devices for the escapements of the operative magazine located in the path of movement of the magazines, and automatic means for shifting the actuating devices out of the path of movement of the magazines when they are shifted.

9. In a typographical machine, the combination of a plurality of magazines, each provided with a series of escapements, and movable as a whole to bring one or another magazine into operative position, a series of actuating devices for the escapements of the operative magazine and located when in operative position in the path of movement of the magazines, a magazine entrance coöperating with the said magazine, and automatic means for shifting both the actuating devices and the magazine entrance from their operative position when the magazines are moved.

10. In a typographical machine, the combination of a fixed assembling throat, a magazine movable into and out of registration therewith and provided with a series of escapements, a series of actuating devices connected to the escapements, and means whereby the movement of the magazine out of registration with the assembling throat will effect the disconnection of the escapements and their actuating devices.

bination of a plurality of magazines, each provided with a series of escapements, means for moving the magazines as a whole to bring one or another into operative position, 5 a series of actuating devices for the escapements of the operative magazine, a magazine entrance coöoperating with said magazine, and means operated directly by the magazine moving means for shifting both 10 the actuating devices and the magazine entrance from operative position.

11. In a typographical machine, the combination of a plurality of magazines, each provided with a series of escapements, 15 means for moving the magazines to bring one or another into active position, a series of actuating devices for the escapements of the active magazine, means for moving said devices from their operative position, a magazine entrance coöoperating with the active 20 magazine, means for moving said entrance from its operative position, and a common operating device connected directly to all the said moving means.

12. In a typographical machine, the combination of a magazine provided with a series of escapements, a series of actuating devices for the escapements, of means for moving the actuating devices out of operative 25 relation to the escapements, a magazine entrance coöoperating with the magazine, 30 means for moving the entrance from its operative position, and direct connections between both said moving means, to insure 35 their simultaneous operation.

13. In a typographical machine, the combination of a plurality of magazines, and means for shifting the magazines to bring one or another into operative position, the 40 said means comprising a pair of rotary cams arranged at each end of the magazines, and connecting links between the two pairs.

In witness whereof I have hereunto set my hand in the presence of two witnesses.

CHRISTIAN AUGUSTUS ALBRECHT.
